UNITED STATES PATENT OFFICE.

JOHN B. CARR, OF PEMBerville, OHIO.

SHUT-OFF FOR OIL-TANKS.

No. 848,723.

Specification of Letters Patent.

Patented April 2, 1907.

Application filed July 19, 1906. Serial No. 326,876.

To all whom it may concern:

Be it known that I, JOHN B. CARR, a citizen of the United States, residing at Pember-ville, in the county of Wood and State of 5 Ohio, have invented a Shut-Off for Oil-Tanks, of which the following is a specification.

This invention is an improvement in oil-tanks, and relates more especially to the provision of an automatic device adapted for the 10 purpose of shutting off the discharge-pipe when the surface level of the oil in the tank reaches a certain point.

The primary objects of the invention are to produce a strong and durable automatic 15 shut-off device which shall be reliable and positive in its operation and can be readily and conveniently applied to the customary type of oil-tank without alteration thereof.

Other objects and advantages of the in- 20 vention will hereinafter appear in the speci- fication, and what I claim as novel in the particular construction and arrangement of parts constituting the invention will be spe- cifically set forth in the appended claim.

25 In the accompanying drawings, which form a part of this specification, Figure 1 is a side elevation illustrating the application of the invention, the full lines showing the parts in their normal position to discharge the con- 30 tents of the oil-tank, while the dotted lines show the automatic device tripped to close the valve in the discharge-pipe. Fig. 2 is a detail sectional view, enlarged, of a support hereinafter referred to. Fig. 3 is a side ele- 35 vation showing a slight modification.

Like numerals of reference indicate like parts in all the views of the drawings.

1 designates the oil-tank, 2 the discharge-pipe, and 3 the valve located in said dis- 40 charge-pipe, these parts being of the usual construction.

In carrying out my invention the squared outer end of the stem 4 of the valve 3 has fitted thereon a lever 5, which is angular in 45 shape to provide the projecting arms or members 6 and 7, and said lever is so connected to the valve-stem that when the valve is open the member 6 will extend at an upward inclination, while the companion mem- 50 ber 7 extends downwardly and rearwardly, as shown in full lines, Fig. 1. The arm or member 6 is shaped at its upper end to engage a shoulder or catch 8 at the outer end of a bent lever 9, the latter being adapted

to hold the valve in its open position and 55 against the action of a closing-spring, herein- after described. The bent lever 9 is loosely pivoted on a pintle 23 at the upper end of a fixture or support 10, adjustably secured on the discharge-pipe 2 between the tank and 60 valve. The fixture 10 has a depending por- tion which terminates in a socket 11 and eye 12, the socket receiving a bar 13, secured therein by frictional engagement and con- stituting a buffer or stop for limiting the 65 throw of the valve-operating lever 5.

The member 7 of the valve-operating lever 5 strikes the buffer 13 when the valve is turned to its closed position, and for the pur- 70 pose of turning the valve automatically from an open to a closed position when the said operating-lever is released from the trip-lever 9 a spring 14 is provided and connected to the end of the member 7 and to the eye 12 of the fixture or support 10. For this pur- 75 pose I may employ either the coiled spring 14 (shown in Fig. 1) or a plate-spring 15, as shown in Fig. 3, in which latter instance the spring is supported in a loop 16 on the fixture 10 and is connected at its ends by chains 17 80 to the member 7 of the valve-operating lever, the connections of the chains 17 being such that when the lever is thrown to the open po- 85 sition of the valve the plate-spring will be bowed or under tension sufficient to throw the lever to the closed position of the valve as soon as said lever is released. It will be understood, of course, that instead of a spring I may employ its equivalent—as, for instance a weight, the application of which will be 90 readily apparent.

From so much of the description it will be readily seen that when the valve-operating lever 5 is turned to open the valve and is en- gaged by the trip-lever 9 the contents of the 95 tank 1 will be discharged through the pipe 2 and that when said valve-operating lever is released by disengaging the trip-lever there- from the spring will act to throw the valve- 100 operating lever and close the valve.

Of course the trip-lever may be operated manually; but in order to provide for an automatic operation thereof when the sur- face level in the oil-tank reaches a certain point I provide a float 18 upon the body of 105 oil in the tank and connect the same by a chain or flexible connection 19 to the outer end of the trip-lever 9, said chain passing

over a guide-pulley 20, located at the upper edge of the tank. There is enough slack in the chain 19 so that the same will not operate on the trip-lever until the level of the oil in the tank reaches a certain point—in the present instance a point slightly above the discharge-pipe, as indicated in dotted lines in Fig. 1.

From the foregoing the operation will be readily understood, for as the oil is discharged through the discharge-pipe the float will follow the fall of oil in the tank, and when the slack in the chain 19 has been taken up the weight of the float will pull upon the trip-lever and release the same from the valve-lever 5, the latter being then thrown by the spring to close the valve in the discharge-pipe. When the tank is to be again filled, the valve is opened and held by the trip-lever, so that the automatic operation may be repeated.

The fixture or adjustable support 10 is preferably made up of two plates, Fig. 2, provided with half-round portions adapted to embrace the discharge-pipe 2 and bar or buffer 13, respectively, said plates being clamped together on said parts by means of the bolts 21 and 22, as shown. The upper ends of the plates are cut away at their inner sides to receive the lever 9, which is pivoted on the pintle 23. It will be seen, therefore, that the support or fixture 10 can be adjusted on the discharge-pipe to properly locate the same with respect to the valve and its operating-lever, and of course the buffer-bar 13 can be adjusted in the support so that the valve will be properly closed when the member 7 of the lever is against the buffer.

As valves are usually provided with square-end stems, it is apparent that the de-

vices hereinbefore described can be readily and conveniently applied to the customary type of oil-tank.

Having described my invention, what I claim as new, and desire to secure by Letters Patent, is—

The combination with an oil-tank having a discharge-pipe extending therefrom and provided with a valve the stem of which is squared at its outer end, of an angle-lever 50 provided centrally with a square opening by which it is applied to the squared end of the valve-stem so as to provide members at the opposite sides of the latter, a supporting-bracket adapted to be clamped upon the discharge-pipe and comprising two similar plates and connecting-bolts, said plates embracing the discharge-pipe and forming a tapered opening near the lower end of the bracket and a pair of ears at the upper end 55 thereof, a wedge-shaped buffer-bar removable engaging the tapered opening of the bracket, a trip-lever pivoted between the ears at the upper end of the bracket and adapted to detachably engage one member of the angle-lever, and a compression-spring connected to the other end of the angle-lever and to the supporting-bracket; together with a float located in the tank, a guide at the upper edge of the tank, and a flexible connection extending from the float over the guide and connected to the trip-lever, as herein shown and described.

In testimony whereof I have signed my name to this specification in the presence of 75 two subscribing witnesses.

JOHN B. CARR.
